AUTOMATIC STENOTYPE PAPER HOLDER

Filed May 27, 1930

2 Sheets-Sheet 2

UNITED STATES PATENT OFFICE

WILLIAM GORDON WAGGONER, OF PHOENIX, ARIZONA

AUTOMATIC STENOTYPE-PAPER HOLDER

Application filed May 27, 1930. Serial No. 456,151.

My invention relates to the art of stenotyping and it particularly has for its object to provide a simple, inexpensive, easily operated, neat appearing device for receiving and holding the paper taken from the stenotype machine in its folded state and maintaining it in a position to be conveniently read by the operator.

Further, the invention has for its object 10 to provide a holder which sustains the paper in an upright reading position and enables the paper to be turned as desired by simply turning a knob on the side of the holder.

Further, it is an object to provide a holder 15 which in one part receives the folded pack taken from the stenotype machine, unfolds it as desired by the operator and refolds it into another pack in another part of the holder and at the same time exposes for reading those portions of the paper strip as extend from one pack to the other.

Other objects will in part be obvious and in part be pointed out hereinafter.

To the attainment of the aforesaid objects 25 and ends, the invention still further resides in the novel details of construction, combination and arrangement of parts, all of which will be first fully described in the following detailed description, then be particularly pointed out in the appended claims, reference being had to the accompanying drawing, in which:—

Figure 1 is a perspective view of my invention in use.

Figure 2 is a vertical longitudinal section of the same.

Figure 3 is a vertical longitudinal section showing a part of strip being conveyed from the lower chamber to the upper chamber in order to expose a new section of strip to view.

Figure 4 is a detail perspective view of a portion of the case showing the partition shelf.

Figure 5 is a detail perspective view of one end of the paper-sheet-loop transferring slide.

Figure 6 is a detail perspective view of the paper holding finger and its actuating cam and spring.

Figure 7 is a detail perspective view of the

holder with the paper removed and showing a modified form of the paper transferring slide.

Figure 8 is a detail perspective view of the upper end of the case showing the opening 55 through which the finished pack may be withdrawn.

In the drawings, in which like numerals of reference indicate like parts in all of the figures, 1 represents the case which is provided about midway of its length with a partition shelf 2 having a depending lip 3 and a forwardly projecting lip 4.

Arranged longitudinally of the case and on the side walls thereof are side guides 5 65 for the paper transferring slide. These guides 5 extend in the same plane to about the middle of the case and there merge with semi-circular slide end guides 6, the purpose of which will presently appear.

A rotatable shaft 7 is mounted in suitable bearings in the sides of the case 1 and is provided with a knob 8 by means of which the shaft may be turned. The shaft also carries cam members 24 at one end, the purpose of which will presently appear.

The shaft 7 is provided with openings 9 for the parallel longitudinal bars 10 of the slides to work in. The slide consists of the parallel bars 10 united by the end bars 11 80 from which end bars forwardly projecting feet extend. These feet consist of the forwardly projecting bars 12, the longitudinal bars 14 and the top and bottom cross bars 13, the latter having a right angled extension 15 85 serving as an edge stop for the paper.

The parts 12, 13, 14 and 15 constitute the major foot. A minor foot is also provided which is spaced from the major foot and consists of a forwardly projecting bar 16, a cross bar 17 and a right angled projecting paper edge stop 18. The stops 15 and 18 lie at opposite edges of the paper strip and the bars 13 and 17 lie in alignment with each other but spaced apart to leave a sufficient opening to enable the feet to pass the forwardly projecting lip 4 of the shelf 2.

19 designates a rock shaft mounted in a suitable bearing in the upper end of the case 1. The rock shaft carries the paper

holding finger 20 which is in the form of a bell crank lever. One portion of this bell crank lever projects through a slot in the side wall of the case 1 and has secured to it pivotally a rod 21, the rod 21 lying along the outside of the case and projecting down so as to have its end held in cooperative relation to the cam 24. The rod 21 is held down into engagement with the cam by a suitable spring 22 and passes through a suitable bearing 23 on the side of the case 1. Normally the lower end of the rod 21 lies against one of the flat faces of the duplex cam member 24 and is adapted to be raised against the spring tension by the cam as the shaft 7 is turned in order to lower the paper holding finger 20 into parallelism and against the side wall of the case 1 while a paper loop is being transferred from the lower compartment to the upper compartment.

The case 1 is sustained in its elevated position with the paper strip in its readable relation to the operator, by means of a supporting foot 25 preferably having suitable rubber bumpers 26 to prevent scratching the desk on which the article is placed. The foot 25 is hinged at 27 to the case 1 and when not in use is adapted to fold up flatwise with the case, a thumb screw 28 being provided to tighten the hinge joint in either of its positions.

29 is a stenotype paper which is folded in loops 30, the exposed face of the paper being indicated by 31 and the creases by 32.

Instead of having the paper transferring slide in the form of a skeleton framework as in the first embodiment of the invention, the slide may be made as a plate 33 from which major feet 34 project at the respective ends, and minor feet 35 also. The feet 34 and 35 are provided with suitable paper side guides 36 corresponding in purpose and function to the guides 15 and 18.

When the plate slide is used the shaft 37 will have a transverse slot 39 in which the body of the slide plate 33 will move. It should be understood that the slot 39 is of such size that the slide 33 will drop through it by gravity and likewise the openings 9 in the shaft 7 will be of such size as to permit the bars 10 freely to slide through the same.

So far as described the manner in which the invention operates will best be indicated as follows:

Assuming that the pack of folded strip has been placed in the lower chamber of the case, with the slide placed in the first fold of the strip, this exposes the first part of the strip to view. Now when it is desired to bring a fresh section of the strip into view the operator turns the knob 8 in a clockwise direction which causes the slide 10 to be swung in the arc of a circle having as its center the axis of the shaft 7 carrying with it the lower fold of the paper. As the shaft is turned and the slide

with the lower fold of paper is moved upwardly, one of the cam elements 24 will force the rod 21 upwardly against the tension of the spring 22 and thereby rock the finger 20 from the horizontal position within the upper loop to a vertical position outside the upper loop of the paper and between it and the adjacent side of the case. In turning from a horizontal to a vertical position the slide 10 will be held from dropping until it has reached its uppermost position because of the engagement of the cross bar 11 with the end guideway 6. Just as the slide reaches its uppermost position the cam 24 will release the rod 21 and permit the spring 22 to function to project the finger into the newly raised loop. This occurs just prior to the time the slide reaches its extreme uppermost position, the loop being held open by virtue of the major and minor feet of the slide. By the time, however, that the slide has reached its uppermost position the cam 24 will have released the rod 21, the finger 20 will have entered the newly raised loop and the slide having been released from the guide 6 will drop by gravity to its lowermost position again into the newly exposed lower loop ready for a repetition of the foregoing operation. See Figure 1.

The operation is repeated from time to time until all of the paper strip from the lower pocket or chamber of the case has been exhibited and folded up into the upper pocket or chamber of the case.

The top of the case is preferably left open save for a strip 40 directly above the location of the finger 20 and the back of the case may be provided with a thumb opening 41 so that when it is desired to remove the contents from the upper chamber this may be done by means of the thumb and forefinger.

From the foregoing description, taken in connection with the accompanying drawings, it is thought the construction, operation and many advantages of my invention will be clear to those skilled in the art to which it appertains.

What I claim is:

1. In holders for stenotype paper, a case having an upper and a lower chamber adapted to receive a pack of zigzag looped or folded paper strip, means for transferring the paper loop by loop from one chamber to the other and exhibiting a face of the strip from one chamber to the other.

2. In holders for stenotype paper, a case having a partition dividing it into two chambers to receive a zigzag folded strip-pack of paper, means for transferring the pack fold by fold from one chamber to the other while exposing one face of that portion of the paper which overlies the chambers.

3. In holders for stenotype paper, a case having a partition dividing it into two chambers to receive a zigzag folded strip of paper,

and means for transferring the paper fold by fold from a lower to a higher chamber, and means for holding the transferred folds against leaving the higher chamber after being transferred thereto.

4. In holders for stenotype paper, a case having an open face, a partition within said case dividing it into a lower and an upper chamber, means holding the case in position for the observation of its contents, a shaft rotatable in bearings in said case and located adjacent said partition, a slide carried by said shaft, said shaft having a passage for said slide to work in, guides on said case for said slide, said slide adapted to gravitate to the lower chamber when parallel thereto, means holding said slide against movement in said shaft while said shaft is being turned, said slide having provisions to enter the loop of a zigzag pack of paper placed in one of said chambers, and means to hold the loops of paper in the upper chamber upon transfer of the same thereto by said slide.

5. In holders for stenotype paper, a case having an open face, a partition within said case dividing it into a lower and an upper chamber, means holding the case in position for the observation of its contents, a shaft rotatable in bearings in said case and located adjacent said partition, a slide carried by said shaft, said shaft having a passage for said slide to work in, guides on said case for said slide, said slide adapted to gravitate to the lower chamber when parallel thereto, means holding said slide against movement in said shaft while said shaft is being turned, said slide having provisions to enter the loop of a zigzag pack of paper placed in one of said chambers, and means to hold the loops of paper in the upper chamber upon transfer of the same thereto by said slide, said last named means comprising a finger adapted for insertion in the loops or folds of the paper, and means to withdraw and insert said finger in harmony with the action of said slide.

6. In holders for stenotype paper, a case having an open face, a partition within said case dividing it into a lower and an upper chamber, means holding the case in position for the observation of its contents, a shaft rotatable in bearings in said case and located adjacent said partition, a slide carried by said shaft, said shaft having a passage for said slide to work in, guides on said case for said slide, said slide adapted to gravitate to the lower chamber when parallel thereto, means holding said slide against movement in said shaft while said shaft is being turned, said slide having provisions to enter the loop of a zigzag pack of paper placed in one of said chambers, and means to hold the loops of paper in the upper chamber upon transfer of the same thereto by said slide, said last named means comprising

ing a finger adapted for insertion in the loops or folds of the paper, a cam on said shaft, and operating connections between said cam and said finger for the purposes described.

7. A holder for paper which is folded zigzag into a pack, said holder adapted to expose a portion of said pack to view; said holder including a case having two chambers one of which is a receiving chamber for initially receiving the folded pack, means for transferring the pack of paper loop by loop from the receiving chamber to the other chamber and exposing one face of the paper to view along the length of said chamber.

8. A holder for paper which is folded zigzag into a pack, said holder adapted to expose a portion of said pack to view; said holder including a case having two chambers one of which is a receiving chamber for initially receiving the folded pack, means for transferring the pack of paper loop by loop from the receiving chamber to the other chamber and exposing one face of the paper to view along the length of said chamber, said transferring means comprising a rotatable shaft, and a slide carried by said shaft.

9. A holder for paper which is folded zigzag into a pack, said holder adapted to expose a portion of said pack to view; said holder including a case having two chambers one of which is a receiving chamber for initially receiving the folded pack, means for transferring the pack of paper loop by loop from the receiving chamber to the other chamber and exposing one face of the paper to view along the length of said chamber, said transferring means comprising a rotatable shaft, a slide carried by said shaft, and means for limiting the concurrent rotation of the slide and shaft to 180° .

10. A holder for paper which is folded zigzag into a pack, said holder adapted to expose a portion of said pack to view; said holder including a case having two chambers one of which is a receiving chamber for initially receiving the folded pack, means for transferring the pack of paper loop by loop from the receiving chamber to the other chamber and exposing one face of the paper to view along the length of said chamber, said transferring means comprising a rotatable shaft, and a slide carried by said shaft, said slide being slidable transversely of said shaft from a position across the upper chamber to a position across the lower chamber, and means to limit the concurrent rotation of said slide and shaft to an arc of 180° .

11. A holder for paper which is folded zigzag into a pack; said holder adapted to expose a portion of said pack to view; said holder including a case having two chambers one of which is a receiving chamber for ini-

- 5 initially receiving the folded pack, means for transferring the pack of paper loop by loop from the receiving chamber to the other chamber and exposing one face of the paper to view along the length of said chamber, said transferring means comprising a rotatable shaft, a slide carried by said shaft, said slide being slidable transversely of said shaft from a position across the upper chamber to
10 a position across the lower chamber, means to limit the concurrent rotation of said slide and shaft to an arc of 180°, said shaft being rotatable through an arc of 360°, and means limiting the direction of rotation of said shaft to one direction only.
- 15 12. A holder for paper which is folded zig-zag into a pack, said holder adapted to expose a portion of said pack to view; said holder including a case having two chambers
20 one of which is a receiving chamber for initially receiving the folded pack, means for transferring the pack of paper loop by loop from the receiving chamber to the other chamber and exposing one face of the paper
25 to view along the length of said chamber, said transferring means comprising a rotatable shaft, and a slide carried by said shaft, said slide comprising a body having projecting feet at its ends, said feet adapted to
30 engage in the loop of paper.
13. A holder for paper which is folded zig-zag into a pack, said holder adapted to expose a portion of said pack to view; said holder including a case having two chambers
35 one of which is a receiving chamber for initially receiving the folded pack, means for transferring the pack of paper loop by loop from the receiving chamber to the other chamber and exposing one face of the paper
40 to view along the length of said chamber, said transferring means comprising a rotatable shaft, and a slide carried by said shaft, said slide comprising a body having projecting feet at its ends, said feet adapted to engage in the loop of paper, said feet having paper edge stops substantially as shown and described.
- 45 14. A holder for stenotype paper comprising a case having an upper and a lower chamber and adapted to receive a pack of zigzag looped or folded paper strip in one of said chambers, means for transferring the strip from the first chamber to the other chamber while exposing one face of the strip to view.
- 50 55 WILLIAM GORDON WAGGONER.
